United States Patent Office

Des. 230,308
Patented Feb. 5, 1974

230,308

ELECTRONIC CASH REGISTER

Lynton Randolph Knapp, Orange, and Ralph Waldo Province, Westminster, Calif., assignors to MSI Data Corporation, Costa Mesa, Calif.

Filed Feb. 10, 1972, Ser. No. 225,365

Term of patent 14 years

Int. Cl. D18—01; D14—02

U.S. Cl. D52—4 A

Fig. 1

Fig. 3

FIG. 1 is a front and side perspective view of an electronic cash register showing our new design, the opposite side being identical thereto;

FIG. 2 is a rear elevational view thereof;

FIG. 3 is a partial top plan view thereof taken from line 3—3 of FIG. 2.

The bottom is plain and unornamented.

We claim:

The ornamental design for an electronic cash register, as shown and described.
